Primary Examiner — Cynthia Underwood(74) *Attorney, Agent, or Firm* — Sughrue Mion, PLLC(57) **CLAIM**

The ornamental design for a plate, as shown and described.

DESCRIPTION

FIG. 1 is a perspective view of a plate.

FIG. 2 is a front elevation view thereof. A rear view is omitted because it is identical with the front elevation view.

FIG. 3 is a left side elevation view thereof. A right side elevation view is omitted because it is identical with the left side elevation view.

FIG. 4 is a top plan view thereof.

FIG. 5 is a bottom plan view thereof; and,

FIG. 6 is a cross-sectional view thereof taken along line 6-6 in FIG. 4.

The broken lines which define the bounds of the claimed design form no part thereof.
